United States Patent Office

Des. 188,550
Patented Aug. 9, 1960

188,550

MODEL FOR A PROPULSION TUBE AIRCRAFT

Joseph T. Yeager, Sr., 37 Stevenson Ave., Trenton, N.J.

Filed Mar. 18, 1958, Ser. No. 50,087

Term of patent 14 years

(Cl. D34—15)

FIG. 1

FIG. 2

FIG. 3

FIG. 4

FIG. 5

Figure 1 is a front perspective view of a model for a propulsion tube aircraft showing my new design;
Figure 2 is a rear perspective view thereof;
Figure 3 is a front elevational view thereof;
Figure 4 is a side elevational view thereof; and
Figure 5 is a front end view thereof.

I claim:
The ornamental design for a model for a propulsion tube aircraft, as shown.
